Application December 23, 1940, Serial No. 371,431

4 Claims. (Cl. 40—96)

This invention relates to new and useful improvements in changeable exhibitors and more particularly to an exhibitor which can be used to display the prices of commodities on store shelves.

The principal object of the present invention is to provide a changeable price exhibitor which can be readily applied to a store shelf and conveniently changed in regard to its display characteristics without removal of the exhibitor from the shelf.

Other objects and advantages of the invention will become apparent to the reader of the following specification.

In the drawings:

Figure 1 represents a fragmentary front elevational view of a shelf showing the exhibitor in displaying position.

Figure 2 is a sectional view taken substantially on line 2—2 of Figure 1.

Figure 3 is a top plan view of the exhibitor.

Figure 4 is a bottom plan view of the exhibitor.

Figure 5 is a longitudinal sectional view taken substantially on line 5—5 of Figure 3.

Figure 6 is a perspective view of the web mover.

Figure 7 is a top plan view of the device constructed as a dual assembly.

Referring to the drawings wherein like numerals designate like parts, it can be seen, for instance, in Figure 1 that numeral 5 denotes a store shelf on which are cans 6 of various commodities. Numeral 7 generally refers to the exhibitor which makes up the present invention and which is adapted to be applied to a store shelf to indicate the price of nearby commodities.

The exhibitor consists broadly of a channeled leg 8 composed of a bottom wall *a*, side walls *b* and an end wall *c*.

Extending upwardly from the forward ends of the side walls *b* are risers 9, 9 connected by a backing plate 10 of arcuate shape and across which sweeps a web 11 on which are various characters or price indications 12.

In vertically spaced relation with respect to the channeled structure 8 is a top leg or plate 13 which has its forward end portion interposed between the risers 9 and suitably secured thereto.

As is clearly shown in Figure 5, the upper and lower ends of the backing plate 10 are spaced from the plate 13 and bottom *a* of the channeled structure 8 to define slots 14 and 15 through which the web 11 passes.

Between the rear end portions of the side walls *b* is interposed a roll 16 over which the web 11 is trained, while between the lower ends of the

risers 9, 9 is mounted a roll 17 under which the top plate of the web 11 is trained.

Numeral 18 generally refers to a mover for the web and this consists of an elongated narrow plate 19 which extends longitudinally on the bottom *a* and has a downturned finger engageable portion 20 at its forward end which depends through the slot 15.

The remaining end of this plate 19 has an enlarged head portion 21 formed with a pair of slots 22, 23 extending inwardly from one side edge portion thereof and defining a finger 24 which is transversely beveled toward its forward edge portion where teeth 25 are provided.

As can be seen in Figure 5, the web 11 extends at its lower flight downwardly through the slot 23 and upwardly through the slot 22. Obviously when the structure is in the position shown in Figure 5, the web is set to be changed.

With the device applied to a shelf as shown in Figure 2, and with the parts set as shown in Figure 5, an outward pull on the finger engageable end portion 20 of the web mover 18 will cause the teeth 25 to slightly bite into the web and cause a counter clockwise movement of the web. Obviously when the mover 18 has been moved outwardly to its fullest extent, it can then be pushed back to the original position as shown in Figure 5 without moving the web and the finger 24 will simply ride over the lower part of the web without in any way gripping the same.

As can be seen in Figure 7, the device can be of a dual construction, and in this connection a channeled structure 8a will be employed in conjunction with a top leg or plate 13a and connecting risers 9a. These risers will be bridged by a backing plate 10a against which a pair of webs 11a, 11a will rise. Similar rolls 16a and 17a are provided for the webs 11a and 11a corresponding to the rolls 16 and 17 shown in Figure 5. A pair of like constructed movers 18a and 18a operating along the bottom of the channeled structure 8a are used one for operating each of the webs 11a.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A changeable exhibitor comprising a substantially U-shaped structure consisting of a pair of parallel legs and a connecting portion, a pair of rolls mounted in longitudinally spaced relation

on one of the legs, said connecting portion being provided with a pair of spaced slots, a web trained over the connecting portion between the slots and extending through the slots, said web being trained over one of the rolls and having both flights trained toward one side of the remaining roll to maintain both flights in close proximity to the adjacent leg portion, said web having characters thereon, and a mover for the web, said mover consisting of a slide plate extending through one of the slots of the connecting portion, said slide plate having means at its inner end for gripping one flight of the web.

2. A changeable exhibitor comprising a substantially U-shaped structure consisting of a pair of parallel legs and a connecting portion, a pair of rolls mounted in longitudinally spaced relation on one of the legs, said connecting portion being provided with a pair of spaced slots, a web trained over the connecting portion between the slots and extending through the slots, said web being trained over one of the rolls and having both flights trained toward one side of the remaining roll to maintain both flights in close proximity to the adjacent leg portion, said web having characters thereon, and a mover for the web, said mover consisting of a slide plate extending through one of the slots of the connecting portion, said slide plate having means at its inner end for gripping one flight of the web, said means consisting of a slotted head for the inner end of the slide plate, said head being slotted to define a finger transversely beveled and provided with teeth at its thin edge adapted to grip one flight of the web.

3. A changeable exhibitor comprising a substantially U-shaped structure consisting of a pair of parallel legs and a connecting portion, a pair of rolls mounted in longitudinally spaced relation on one of the legs, said connecting portion being provided with a pair of spaced slots, a web trained over the connecting portion between the slots and extending through the slots, said web being trained over one of the rolls and having both flights trained toward one side of the remaining roll to maintain both flights in close proximity to the adjacent leg portion, said web having characters thereon, a mover for the web, said mover consisting of a slide plate extending through one of the slots of the connecting portion, said slide plate having means at its inner end for gripping one flight of the web, said means consisting of a slotted head for the inner end of the slide plate, said head being slotted to define a finger transversely beveled and provided with teeth at its thin edge adapted to grip one flight of the web, said teeth being on the edge portion of the finger opposed to the slot through which the plate is slidable.

4. A changeable exhibitor comprising a substantially U-shaped structure consisting of a pair of parallel legs and a connecting portion, said connecting portion being provided with a pair of spaced slots, a pair of webs, each of the webs having a portion disposed across the connecting portion and through the slots, rolls mounted on one of the legs against which the webs are trained, and a mover slidable through one of the slots for each of the said webs.
